UNITED STATES PATENT OFFICE.

ERNEST G. GOODWIN, OF BROOKLYN, NEW YORK, ASSIGNOR TO STANDARD COUPLER CO., OF NEW YORK, N. Y., A CORPORATION OF NEW JERSEY.

DRAFT RIGGING FOR RAILWAY CARS.

Application filed April 18, 1922. Serial No. 555,375.

This invention relates to improvements in apparatus for yieldingly resisting stresses and more especially in some of its details to improvements in draft gears of the friction type adapted for use in connection with railway rolling stock.

The invention has for its general object the provision of an improved draft gear of the class mentioned which is strong, light, compact, wear resistant, and susceptible of ready repair when damaged, and the parts whereof are readily interchangeable with those of old gears of similar type.

Another object is the provision of an improved spring-barrel for draft gears of the class mentioned which is simple and durable and adapted for ready interchange with spring-barrels in draft gears of similar type.

Still another object is the provision of an improved spring-barrel for draft gears of the class mentioned which is rugged and satisfactory in service, and susceptible of construction from standard metallic stock resulting in economies in manufacture.

Another object is the provision of an improved construction of spring-barrels for draft gears giving a maximum of strength with a minimum of material and permitting an increase in spring capacity without sacrificing strength.

Other objects will be in part obvious from the following detailed description of an illustrative embodiment of the invention and in part pointed out in connection therewith.

The invention accordingly consists in the features of construction, combinations of elements and arrangement of parts which will be exemplified in the construction hereinafter set forth, and the scope of the application of which will be indicated in the following claims.

In the accompanying drawings forming a part of this specification wherein several illustrative embodiments are shown,

Figure 1 is a fragmentary side elevation of a draft gear embodying the invention,

Fig. 2 is a central horizontal section through the spring barrel, certain parts being shown in elevation;

Fig. 3 is a transverse section of the spring barrel taken approximately on the line 3—3 of Fig. 2 looking in the direction of the arrows;

Fig. 4 is a transverse vertical section show-

ing the relation of the spring barrel and draft sills, and

Figs. 5, 6, 7 and 8 are detailed enlarged sectional views showing modifications of the spring barrel construction.

Referring now to the drawing for a detailed description, the preferred embodiment of the invention is shown in Figures 1 to 4 inclusive. As there shown the draft gear is disposed between the longitudinal draft sills 1 and 2 of a car in a manner known in the art. The usual stops 3 are secured to the draft sills and positioned to co-operate and form stops for the forward and rear follower plates 4 and 5 respectively, limiting the movement of the rigging in both forward and rearward directions, and functioning to transmit draft and buffing stresses to the under-framing of the car through the resilient elements of the draft gear. Draft and buffing stresses are communicated to the follower plates and thus to the draft rigging through a draw-bar 6, to the rear extremity of which is secured a yoke 7 embracing the stress resisting elements of the rigging.

The primary stress resisting elements of the rigging are shown as comprising concentrically arranged springs 8 and 9 oppositely coiled and seated at one end of the rigging against the follower plate 4. At their opposite ends the springs are seated against the center friction block 10 forming one of the elements of the friction mechanism. As understood by those skilled in the art, friction type of draft gear to which this invention is applied, comprises friction elements co-operating with each other under draft and buffing stresses and arranged to compress the primary resisting elements or springs to a greater degree than the movement of the draw-bar, thus offering a greater resistance to such stresses than could be secured by the mere augmentation of spring resistance. By this means the absorption of heavy buffing and draft stresses is provided for without the employment of excessively heavy springs and other parts.

As shown this friction mechanism includes the center friction block 10 and two oppositely disposed wedge-shaped side friction blocks 11. There is also provided a friction box 12 encompassing the friction blocks and having inclined friction faces co-operating frictionally with adjacent in-

clined friction faces of the side blocks. The blocks and friction box are assembled as shown in Fig. 2, the center block forming a seat for the draft springs and the side blocks being positioned in the wedge-shaped seats between the opposed oppositely inclined friction faces of the center block and friction box, and are in frictional engagement with the same. In this embodiment the center block is constructed of forged steel and the friction box may be of similar construction, while the side friction blocks are of cast metal. This arrangement of parts decreases the cutting and wear of the engaging surfaces under the severe use to which the apparatus is subjected in actual operation. The center block is also provided with a central cavity or pocket, providing a lighter construction. This pocket 23 may also form a seat for the central draft spring.

A housing or spring barrel 13 for the spring is seated at one end against the friction box, a seat being provided for this purpose; and at the opposite end it is seated against the follower 4. This barrel is of special improved construction approximately rectangular or polygonal in cross section and made up of wrought metal plates bent into form to provide the shape of barrel desired and secured together at their edges. The barrel may also be made up of a single wrought metal plate bent to form the barrel and secured together at adjacent edges as shown, for example, in Fig. 5.

As shown in Figs. 3 and 4 the plates forming the barrel are shaped at diagonally opposite corners of the latter to form longitudinal corrugations or stiffening columns 14 and at the other diagonally opposite corners the plates are overlapped as at 15 and secured together, as by rivets, forming a rigid structure. For this purpose the edge of one of the plates is offset outwardly 45 forming an offset flange 16 overlapping the adjacent edge of the companion plate. This arrangement of overlapping edges provides additional longitudinal stiffening columns disposed at corners of the barrel functioning also as longitudinal reinforcing columns for receiving service stress. Intermediate the longitudinal corner columns additional stiffening columns may be provided by forming outwardly extending ribs or corrugations 17 corresponding to the contour of the outer spring 8, as shown in Fig. 3.

As particularly shown in Fig. 4 the space between the draft sills 1 and 2 forms a box for receiving the draft rigging, spring barrel being disposed therein, as shown, the columns formed by the overlapping edges of adjacent plates lying substantially at the corners of the draft rigging box, and the corner columns 14 occupy similar positions, while the intermediate corrugations or ribs

17 are disposed on central vertical and horizontal planes passing through the rigging. The corner columns will be positioned on the diagonal planes lying between the vertical and horizontal planes mentioned, but these may be formed otherwise than as shown. Advantage is thus taken of the extra space provided at the corners of the draft rigging box for providing additional cross sectional area of the barrel without utilizing such space as would make it necessary to reduce the size and capacity of the springs. This type of spring barrel could not be installed in existing draft gears of this type if the walls thereof, except at the corner portions, were increased in thickness over the thickness of the walls of the standard cylindrical type of barrel now in use. This is an important feature since the space provided for draft gears of this character is limited and the thickness of the barrel walls could not be increased without correspondingly decreasing the diameter of the springs, impairing the gear.

In order to provide the friction box with a seat for accommodating this special spring barrel two opposed lips or lugs 18 project from the inner face thereof, being curved at the central portion complementary with the ribs 17 so as to engage snugly there-around and hold the parts in properly assembled relationship. These lugs are made extra long and formed with reversely curved lateral portions 19 co-operating with walls of the barrel as the latter recede from the contour of the spring 8. The lugs therefore engage with the spring barrel substantially throughout their length forming a firm seat particularly well adapted to hold the barrel securely in position. Also the yoke 7, encompassing the spring barrel and friction box and follower plates, aids in securing the parts in properly assembled relationship.

It will therefore be perceived that not only is the friction box adapted to receive the improved spring barrel, but also is as well adapted to receive the old cylindrical type of barrel, the curved central portion of the lugs 18 engaging the periphery of the cylindrical barrel to hold the same firmly in position. Therefore, with the type of friction box herein disclosed, the new type of spring barrel is interchangeable with the old cylindrical type, and other parts of the new rigging are also interchangeable with parts of the old gear. It will also be obvious that the new gear may be interchanged as a whole with an old gear of this type. This interchangeability of parts is important inasmuch as the repairs and replacements are facilitated in existing installations of the old type of gear, or in installations of the new type of gear. The new gear is also advantageous over the old type from a standpoint of manufacturing cost, since the

improved barrel may be made up of standard wrought metal plates procurable in the open market at a minimum price, whereas the old cylindrical barrel has to be specially made involving extra expense. Due to the system of reinforcing above explained the barrel is increased in strength over that of the old type of barrel, while the weight thereof is only slightly increased and for equal strength may be considerably reduced.

In the modification shown in Fig. 5 the spring barrel is made up of a single wrought metal plate bent into proper shape to form the spring barrel and having overlapping secured edges 15 provided by the offset flange 16, as already described.

In Fig. 6 the barrel is made up of a single wrought metal plate bent into shape with the edges abutting and welded together as indicated at 20. In order to provide an additional reinforcement a strip 21 may be placed in the angle between the edges of the plate and welded thereto. It is obvious that the barrel thus formed may be made up of two or more plates welded together at adjacent edges if desired.

Fig. 7 shows still another method of securing the adjacent edges of the wrought metal plates of which the barrel is made. In this case a steel angle bar 22 is interposed between adjacent edges of the barrel plates and the flanges of the angle bar are spot welded to the respective barrel plates as indicated at 23.

According to the modification of Fig. 8 the overlapping edges 24 and 25 of the barrel plates are spot welded as indicated at 26, the welded seam being disposed at the corner of the barrel as in embodiments described above.

As many changes could be made in the above construction any many apparently widely different embodiments of this invention could be made without departing from the scope thereof, it is intended that all matter contained in the above description or shown in the accompanying drawings shall be interpreted as illustrative and not in a limiting sense.

It is also to be understood that the language used in the following claims is intended to cover all of the generic and specific features of the invention herein described, and all statements of the scope of the invention which, as a matter of language, might be said to fall therebetween.

Having described my invention, what I claim as new and desire to secure by Letters Patent is:

1. As an article of manufacture, a friction box for optional application to a tubular type of spring barrel or a substantially rectangular barrel having rounded outer faces intermediate its corners, said friction box including a body, and lugs extending from

said body and shaped for engagement with the side faces of the barrels.

2. As an article of manufacture, a friction box to be applied to a spring barrel, said box including a substantially rectangular body, and a pair of lugs extending outwardly from the side edges of said body at points substantially intermediate the corners thereof, said lugs each including lateral portions, and a central transverse portion curved to be complementary to the adjacent and similarly curved face of the spring barrel.

3. In combination, a spring barrel, including a rigid body formed of sheet metal of constant gauge, said body being substantially rectangular in cross section and being bent to provide longitudinal corrugations extending lengthwise of its body and at points substantially intermediate the corners thereof, a coil spring disposed within said body and adapted to be guided by the skeleton cylinder provided by the curved inner faces of said body, a friction box at one end of said barrel, and friction blocks cooperating with said box and engaged by said spring.

4. As an article of manufacture, a spring barrel for use in draft rigging, said barrel including a rigid body formed of sheet metal of substantially constant gauge and bent to provide rigidifying portions extending lengthwise of said barrel.

5. As an article of manufacture, a spring barrel for use in draft rigging, said barrel including a rigid body formed of sheet metal of substantially constant gauge, said body being substantially rectangular in cross-section and being bent to provide reinforcing portions extending lengthwise of said barrel and disposed adjacent and between the corners of said body.

6. In a friction draft gear, in combination, a spring barrel, a closure at one end thereof, said barrel in cross-section being approximately a square convexly rounded at its four corners and also midway of its four sides, said eight roundings providing longitudinal corrugations for said barrel, a friction box at one end of said barrel, cooperating friction blocks disposed within said box, a helical spring bearing against one of said blocks and located within said barrel and guided by the inner faces of certain of said corrugations, said friction box having on its inner face a seat conforming to and abutting against the end of said corrugated barrel, and two opposite extensions forming a part of said box and conforming to and overlapping the outside of two of the midway corrugations of the barrel.

7. In a friction draft gear, in combination, a spring barrel, a closure at one end thereof, said barrel in cross-section being approximately a square convexly rounded at its four corners and also midway of its four sides, said eight roundings providing corrugations

extending longitudinally of said barrel, a friction box secured at the other end of said barrel, friction blocks within said box, a helical spring arranged between said closure and the inner face of one of said blocks and located within said barrel and guided by the skeleton cylinder provided by the inner faces of said four midway corrugations, said friction box having on its inner face a seat 5 forming to and abutting against the end of said corrugated barrel, and extensions forming a part of said box and conforming to and overlapping certain of the corrugations of the barrel.

15 8. In a friction draft gear, in combination, a spring barrel, a closure at one end thereof, said barrel in cross-section being approximately a square convexly rounded midway of its four sides, to provide corrugations extending longitudinally of said barrel, a friction box secured at the open end of said barrel, friction blocks within said box, and a helical spring engaged between said closed end and the inner face of one of said blocks and located within and guided by the skeleton cylinder provided by the interior faces of said corrugations.

20

friction box secured at the other end of said barrel, friction blocks within the same, and a helical spring engaged between said closure and the inner face of one of said blocks and located within and guided by the inner faces of said four midway corrugations.

9. In a friction draft gear, in combination, a spring barrel, a closure at one end thereof, said barrel in cross-section being approximately a square convexly rounded midway of its four sides, to provide corrugations extending longitudinally of said barrel, a friction box secured at the open end of said barrel, friction blocks within said box, and a helical spring engaged between said closed end and the inner face of one of said blocks and located within and guided by the skeleton cylinder provided by the interior faces of said corrugations.

40
In testimony whereof I affix my signature.
ERNEST G. GOODWIN.
